UNITED STATES PATENT OFFICE.

JAMES THOMAS, OF PITTSBURG, KANSAS, ASSIGNOR TO MORSE TWIST DRILL & MACHINE COMPANY, OF NEW BEDFORD, MASSACHUSETTS, A CORPORATION OF MASSACHUSETTS.

COMPUTING DEVICE.

1,382,331.

Specification of Letters Patent. Patented June 21, 1921.

Application filed November 22, 1919. Serial No. 340,026.

To all whom it may concern:

Be it known that I, JAMES THOMAS, a citizen of the United States, and resident of Pittsburg, in the county of Crawford and State of Kansas, have invented certain new and useful Improvements in Computing Devices, of which the following is a specification.

This invention relates to an instrument or device which is employed for computing numbers; and the object of this invention is to provide a simple and inexpensive instrument which can be conveniently manipulated for the purpose of accurately adding either common or decimal fractions by the simple manipulation of a rotatable disk.

With these and other objects in view, the invention consists of certain novel features of construction, as will be more fully described, and particularly pointed out in the appended claims.

In the accompanying drawings:

Figure 1—is a face view of my improved computing device.

Fig. 2—is a sectional edge view on line 2—2 of Fig. 1.

Fig. 3—is an enlarged view showing a portion of the rotatable disk in position to coöperate with the counter member.

Fig. 4—is an enlarged edge view showing one of the counter-operating fingers in position beneath the rotatable disk and engaging the rotatable counter.

Fig. 5 is an enlarged fragmentary view of a modification of the invention.

Referring to the drawings, 10 designates a supporting base or back-plate which may be made of any suitable, rigid material such as wood, cardboard or the like. The face or upper plate 11 of this device is preferably formed of celluloid or other transparent material, the same being provided with a semi-circular slot 12 formed through its surface.

Beneath this face-plate is another plate or sheet 13 having an annular slot 13^a therein of substantially the same radius as the semi-circular slot 12, and lying beneath it. On the outer face of said plate 13 and, preferably, on the outer side of the slot 13^a is provided a circular graduation 13^b. This graduation, consisting of two duplicate scales, x and y , progressively extending from opposite sides of a setting point 30, at one end of the semi-circular slot 12, to the other end

of the said slot 12. The scale y adjacent the slot 12 is what is termed "a calculating scale" (as the calculations are made with this scale), and the scale x on the opposite side of the slot is what is termed "an indicating scale" (as the fractional results of the addition is indicated thereon, as will be later observed).

Beneath this graduated plate 13 I have rotatably mounted a disk 14 on the pivot pin 15, which disk is provided with a series of holes 16 formed on a circle whose radius is substantially that of the slot 12 in the outer plate, said holes being for the purpose of receiving the point of an operating instrument 19 such as a pencil or the like as shown in dotted lines in Fig. 2, whereby the disk may be rotated and these holes are spaced apart so as to register with the numbered graduations on the member 13. Two holes 17 and 18 are formed on the disk on diametrically opposite sides of the circle and are marked Zero to designate the starting positions of the disk; that is, when starting a computation these zeros 17 and 18 must be at opposite ends of the slot 12, respectively, one lying opposite the setting point 30.

In order that the device may be capable of adding fractions amounting to more than a whole number, I have provided a counter 20 which is in the form of a disk pivoted at 21 and is provided with teeth or projections 22 on its periphery whereby when the disk 14 has made a one-half revolution, a finger-member 23 on the disk opposite one of the zero points engages the teeth of this counter 20 and rotates it one tooth, thereby causing it to indicate the whole number through the opening 24 in the outer plate. There is a finger member 23 opposite each of the zero points or indicators 17 and 18.

Another opening 25 has been formed in the face-plate through which the point of a pencil or other instrument may be inserted to engage the teeth of the counter and rotate it back to zero position ready for another counting operation after having been operated.

In operating my improved fraction computing device I set the two zero marks 17 and 18 of the disk 14 at opposite ends of the slot 12 formed in the top plate. Now if I wish to add $5/8$ and $49/64$ together I first place the operating pointer in the hole op-

posite the $5/8$ graduation and rotate the disk downwardly until the pointer engages the end of the circular slot in the outer plate which acts as a stop, and the hole in which it engages is brought in radial alinement with the zero point 30, preferably positioned at the lower end of said slot. I then place the pointer in the hole in the disk opposite the fraction $49/64$ and again rotate the disk downwardly until the pointer engages the end of the slot, in the manner above stated. It will be noted that during this second movement the counter-operating finger 23 opposite the zero mark 17 has passed the counter 20 and in passing engages a tooth thereof and rotates the counter to bring the numeral 1 into position to be observed through the opening 24 and the zero point 17 is passed along to the graduations on the left half of the circle where it points to the fraction $25/64$, thus showing at a glance that the sum of $5/8$ and $49/64$ equals $1 \frac{25}{64}$. If now it is desired to add $41/64$ to this sum it is only necessary to place the pointer through the slot into the hole opposite to that fraction, then by rotating the disk until the point brings up against the lower end of the slot, the second zero mark 18 with its counter-operating finger 23 has passed the counter to the point $1/32$ and as it passed the counter its finger 23 rotated the same one tooth bringing the numeral 2 into view through the opening 24, thus showing that the sum of the three fractions equals $2 \frac{1}{32}$.

To reset the device to normal it is only necessary to engage the teeth of the counter through the opening 25 and rotate it back to show zero which is observed through the opening 24.

I then rotate the disk 14 so that the two zeros 17 and 18 are at the ends of the slot 12 when the device is ready for another calculation.

I have shown and described a transparent outer or top plate with a separate sheet, card or member located beneath it carrying the numbered graduations, but I do not wish to be restricted to this particular construction, as the device may be made in the manner shown in Fig. 5 or any other suitable manner which falls within the scope of the appended claims. In Fig. 5 the transparent plate 11 is dispensed with, but a projection 31, extending from the edge of the plate 13, provides a suitable stop in lieu of the lower end of the slot 12, as will be readily understood.

These different superimposed plates may be connected together by rivets, pins or any other suitable fastenings.

The device is extremely simple and inexpensive in construction and practical and efficient in its operation and by its use frac-

tions may be quickly added and the result accurately determined.

I claim:

1. A computing device of the character described comprising a plate having numbered graduations arranged in a circle thereon, said graduations consisting of two duplicate scales progressively extending from opposite sides of a setting point on the plate to a point opposite said setting point, a rotatable disk having graduations thereon spaced to correspond with said first graduation and to register therewith, said disk further having diametrically opposite indicators thereon, one of which initially registers with said setting point, the graduations on the disk co-operating with one of said scales and said setting point in the calculating operation, and said indicators successively co-operating with the other of said scales to indicate the fractional results of the calculation, counter-operating members on the disk, and a counter mounted on the device and actuated by said counter-operating members, when by a plurality of movements of said rotary disk in adding fractions, the result is greater than a digit.

2. A computing device of the character described, comprising a back plate, a transparent face plate having a semi-circular slot formed therethrough, numbered graduations arranged in a circle of substantially the radius of said slot, a rotatable disk having openings arranged to coincide with said slot and to receive the point of an operating instrument and spaced to register with said graduations, said openings being engageable through said slot, one end of said slot constituting a setting point and a stop engageable by the instrument for limiting each computing movement of the disk, said disk further having diametrically opposite indicators thereon to co-operate with the graduations for indicating certain results, and one of which indicators is to initially register with said setting point, counter-operating fingers on said disk, a toothed rotatable counter adapted to be rotated by the passage of said fingers thereby, whereby a plurality of movements of said disk to add together two or more fractions, where the sum is equal to or greater than a digit, causes said counter to be rotated to show the whole number and the additional fractions being indicated on the graduations by one of said indicators beyond said stop.

In testimony whereof I affix my signature in presence of two witnesses.

JAMES THOMAS.
